UNITED STATES PATENT OFFICE.

EDWIN R. GILBERT, OF CHICAGO, ILLINOIS.

FUSE FOR PROJECTILES.

1,226,652.

Specification of Letters Patent. Patented May 22, 1917.

Application filed November 29, 1916. Serial No. 134,049.

To all whom it may concern:

Be it known that I, EDWIN R. GILBERT, a citizen of the United States, residing at Chicago, in the county of Cook and State of Illinois, have invented a certain new and useful Improvement in Fuses for Projectiles, of which the following is a full, clear, concise, and exact description, reference being had to the accompanying drawings, forming 10 a part of this specification.

My invention relates to certain improvements in fuses for shells, etc., and has for its object the provision of a firing pin which will be maintained in unarmed condition 15 until the shell is subjected to rapid rotation whereupon the firing pin is rendered operative and permitted to fulfil its function when the flight of the projectile is suddenly arrested, as when it strikes an object.

20 In the preferred form of my invention I provide a hammer block having mounted thereon a firing pin and a pair of centrifugal arms, one positioned on each side of the firing pin, the arms being so positioned 25 and constructed as to project beyond the firing pin to render the firing pin inoperative when the hammer block is moved toward the fulminating percussion cap with which the firing pin is adapted to coöperate, 30 before the shell is fired. Upon rotation of the shell and the subjection of the centrifugal arms to centrifugal force the arms are arranged so that they will retract to uncover the firing pin so that after a shell has been 35 fired from a rifled gun the firing pin will strike the cap when movement of the projectile is arrested.

A further object of the invention is the provision of means for locking the centrifugal arms in their advanced position or in a 40 position where they uncover the firing pin so that if for any reason the rotation of the shell discontinues or lessens to an extent such that the centrifugal arms will not be held out by centrifugal force the locking means will serve to retain the arms in their 45 retracted position.

A further object of the invention is the provision of centrifugal arms which when 50 subjected to centrifugal force will move the firing pin away from the fulminating percussion cap so that upon the sudden arrest of the projectile the firing pin will have a sufficient movement relatively to the cap or

the cap relatively to the firing pin so that 55 firing of the cap will take place.

These and other objects of the invention will be more fully set forth in connection with the accompanying drawings wherein,

Figure 1 is a longitudinal cross sectional view of the nose of a projectile embodying 60 the device of my invention;

Fig. 2 is an enlarged plan view of the hammer block carrying the firing pin and the centrifugal arms;

Fig. 3 is a cross sectional view taken along the line 3—3 of Fig. 2 looking in the direction indicated by the arrows. The centrifugal arms in this figure are shown in their normal position, that is, in a position where 70 they project beyond the firing pin and thus prevent its operation;

Fig. 4 is a view similar to Fig. 3 showing one of the centrifugal arms moved to its retracted position; and

Fig. 5 is a view similar to Fig. 4 showing both arms moved to their retracted position and locked in such position whereby the firing pin may, when the hammer block is moved toward the percussion cap, fire the 80 cap.

Similar characters of reference refer to similar parts throughout the several views.

Referring first to Fig. 1, 6 illustrates a casing containing the chambers 7 and 8 85 positioned concentrically, the former above or in front of the latter. The chamber 7 has projecting forwardly from its rear wall a firing pin 9 arranged to engage a fulminating percussion cap carried by the longitudinally movable sleeve or cap support 10 provided with a chamber 11 arranged to contain fulminating powder. The upper end of the chamber 7 is formed by the cap 12 screw-threaded onto the casing 6 as shown. Positioned around the casing 6 and interposed between the cap 12 and the shoulder 13 of the casing is a pair of adjustable rings 14 and 15, each containing the annular chambers 16—16 which are filled with powder. One of the chambers 16 associated with the ring 14 communicates with a passageway 17 extending downwardly and communicating with the space 18 provided around the chamber 8. This passageway 17 and annular space 18 is filled with powder, as are the passageways 19—19 extending through the plug 20 screw-threaded into the

lower end of the casing 6, the plug 20 forming the rear wall of the chamber 8. The mechanism just described constitutes the timing element of the shell and operates in the following manner: The percussion cap holder 10 normally assumes the position illustrated in Fig. 1 so that when the shell is fired the cap holder 10 is moved rearwardly relatively to the casing 6 due to the sudden forward movement of the shell. When the percussion cap contained by the sleeve 10 strikes the firing pin 9 the charge contained within the chamber 11 is ignited and the ignition carried through the several annular chambers 16 down through the passageways 17, 18, and 19 to the body of the shell. The chambers 16—16 of the rings 14 and 15 communicate with one another at certain points and since the rings 14 and 15 are movable 10 relatively to the other and relatively to the casing 6 the device may be adjusted so that the ignition reaches the body of the shell at a predetermined time interval after the shell is fired.

That portion of the casing 6 which forms the forward end wall of the chamber 8 supports the sleeve 21 carrying at 22 a percussion cap arranged to ignite powder contained within the receptacle 23 formed by the sleeve 21. Arranged to move longitudinally within the chamber 8 is a hammer block 23 provided at its foremost side with a slot or groove 24. Centrally located with respect to the hammer block and extending upwardly from the base of the groove 24 is a firing pin 25, this pin projecting upwardly beyond the extreme front end of the hammer block, as shown in Figs. 3 to 5 inclusive. The centrifugal mechanism for controlling the operation of the firing pin is shown at 26 and is mounted on the hammer block in the slot or groove 24. This centrifugal mechanism consists of the two arms 27 and 28, one positioned on each side of the firing pin 25. The arm 27 is pivoted at 29 to a post or stud 30, and the arm 28 is pivoted at 31 to the post or stud 32, the studs 30 and 32 in the preferred form of my invention being inserted into apertures contained by the block 23 and secured in such position in any suitable manner, as most clearly shown in Fig. 3. The arms 27 and 28 are connected by means of two helical springs 33 and 34, the tendency of the springs being to move the arms toward each other or toward the firing pin.

In assembling the device the centrifugal arms 27 and 28 are placed in the position shown in Fig. 3 and are held in such position by means of the springs 33 and 34. The firing block is then inserted into the chamber 8 and the block 20 screw-threaded into place. Attention is called to the fact that when the arms 27 and 28 are in the position shown in Fig. 3 they project out-

wardly beyond the point of the firing pin 25 so that if the hammer block is moved toward the percussion cap 22 no ignition thereof will occur since the firing pin is not permitted to engage the cap. When the shell is fired from a rifled gun it is caused to rotate and this rotation subjects the arms 27 and 28 to centrifugal force which moves the arms outwardly against the tension of the springs 33 and 34 to the position illustrated in Fig. 5. The movement of the arms 27 and 28 from the position shown in Fig. 3 to the position shown in Fig. 5 places the springs 33 and 34 on the underside of the pivots 29 and 31 or on the side opposite that which they formerly occupied. This arrangement of the several parts serves to lock the arms in the position shown in Fig. 5 after they have once been moved to such position. When, therefore, the shell strikes an object the hammer block moves forwardly and the cap 22 is ignited by the firing pin 25. The chamber 23 of the sleeve 21 communicates with the passageway 35 in turn communicating with the annular chamber 18. This passageway is filled with powder so that upon ignition of the percussion cap 22 the charge contained within the body of the shell is ignited.

If for any reason one of the arms 27 and 28 is moved to its retracted position it will be returned immediately since the springs 33 and 34 will, upon movement of one of such arms, assume a position above the pivots of the centrifugal arms. The springs are moved below the pivots only when both of the arms are retracted. If desired, one or a pair of helical compression springs may be interposed between the hammer block and the forward end of the chamber 8 so as to normally hold the hammer block away from the percussion cap. The provision of such springs, however, is avoided when employing the centrifugal arms of my invention. When the arms are moved from the position illustrated in Fig. 3 to the position illustrated in Fig. 5 the extreme outer ends of the arms 36—36 move along the paths shown by the dotted lines 37—37 so that if for any reason the hammer block assumes a position against the forward wall of the chamber 8 the block will be moved rearwardly due to the spreading of the arms 27 and 28.

I have described and illustrated in Fig. 1 two separate and independent means for exploding the shell and I have found it desirable to employ both of these means so that if the shell is not fired by the timing element it will be fired by the hammer block 23. It is, of course, understood that the hammer block 23, together with its percussion cap, may be used without the time igniter.

Devices of this general character employed in the past have been found to be un-

reliable in that explosion of the shell did not always take place and the reason for such ineffective operation has been that binding occurs either between the several parts constituting the centrifugal means or between the centrifugal means and the hammer block. It is to be observed that no binding of any kind can take place between the elements constituting the centrifugal device of my invention, nor between the centrifugal device and the hammer block.

Having thus described my invention what I claim as new and desire to secure by Letters Patent of the United States is:

15. 1. A fuse for projectiles having a hammer, a firing pin mounted thereon, and a centrifugal arm carried by the hammer and arranged to project normally above the firing pin to prevent operation thereof and to 20 retract below the firing pin when the hammer is rotated.

2. In a fuse for projectiles the provision of a casing having a chamber and a support for a percussion cap at the forward end 25 thereof, a hammer longitudinally movable within the chamber, a firing pin mounted on the hammer and adapted to strike the percussion cap, and a centrifugal arm normally interposed between the firing pin and the forward end of the chamber to prevent engagement between the firing pin and percussion cap and arranged to retract in a direction parallel to the direction of movement of the hammer to permit such engagement when the casing is rotated.

3. In a fuse for projectiles the provision of a casing having a chamber, a hammer longitudinally movable within the chamber, a percussion cap and firing pin therefor, one 40 of which is mounted on the hammer and the other on the forward end wall of the chamber, and a centrifugal arm normally interposed between the firing pin and the percussion cap to prevent engagement thereof and arranged to retract in a direction parallel to the direction of movement of the hammer to permit such engagement when the casing is rotated.

4. A hammer block for projectile percussion caps comprising a base, a firing pin mounted thereon, and a centrifugal arm mounted on the base normally projecting above the firing pin and adapted by centrifugal force to retract below the pin to 55 uncover the firing pin.

5. A hammer for projectiles comprising a block, a firing pin centrally mounted on the block, a pair of centrifugal arms pivoted to the block, one on each side of the firing pin, and normally projecting above the firing pin to prevent engagement thereof with a cap, and a spring for holding the arms in such position, said arms being arranged to retract below the pin against the tension 60 of the spring to uncover the firing pin when

the block is rotated and the arms subjected to centrifugal force.

6. A hammer for projectiles comprising a block, a firing pin mounted on the block, a pair of centrifugal arms pivoted to the block, one on each side of the firing pin and normally projecting above the firing pin to prevent engagement thereof with a cap, and a spring connecting the arms to hold them normally in such position, said arms being arranged to retract below the pin against the tension of the spring to uncover the firing pin when the block is rotated and the arms subjected to centrifugal force.

7. A hammer for projectiles comprising a block, a firing pin mounted on the block, a pair of centrifugal arms pivoted to the block, one on each side of the firing pin and normally projecting beyond the firing pin to prevent engagement thereof with a cap, and a spring connecting the arms to hold them normally in such position, said arms being arranged to retract against the tension of the spring to uncover the firing pin when the block is rotated and the arms subjected to centrifugal force, and the parts arranged so that the spring will upon such retraction of the arms assume a position on the opposite side of the pivotal connections between the arms and the block whereby the arms are locked in retracted position.

8. A hammer for projectiles comprising a block having a slot in one of its end faces, a firing pin carried by the block and positioned in the slot, a centrifugal safety device carried by the block and positioned in the slot, said device consisting of a pair of centrifugal arms pivoted to the block, one on each side of the firing pin and normally projecting above the firing pin to prevent engagement thereof with a cap, and a spring for holding the arms in such position, said arms being arranged to retract below the pin against the tension of the spring to uncover the firing pin when the block is rotated and the arms subjected to centrifugal force.

9. In a fuse for projectiles the provision of a casing having a chamber, a hammer longitudinally movable within the chamber, a percussion cap and firing pin therefor, one of which is mounted on the hammer and the other on the forward end wall of the chamber, and a centrifugal arm arranged 115 when operated to move the hammer away from the said end wall of the chamber when the hammer is resting against the said wall of the chamber upon rotation of the projectile.

10. In a fuse for projectiles the provision of a casing having a chamber and a support for a percussion cap at the forward end thereof, a hammer longitudinally movable within the chamber, a firing pin mounted 120

on the hammer, and a centrifugal arm carried by the hammer arranged when operated to move the hammer and thus the pin away from the forward end of the chamber when 5 the hammer is positioned against the said wall of the chamber upon rotation of the projectile.

In witness whereof, I hereunto subscribe my name this 24th day of November, A. D. 1916.

EDWIN R. GILBERT.
